TWO-WAY INTERCOMMUNICATING LOUD-SPEAKER SYSTEM FOR POWER CIRCUITS

Sol. J. Levy, New York, N. Y., assignor to International Carrier-Call and Television Corporation, a corporation of New York

Application May 23, 1936, Serial No. 81,350

6 Claims. (Cl. 179—2.5)

This invention relates to two way communication, and more particularly to carrier frequency communication apparatus and systems operating on electric networks or other metallic transmission media.

5 One of the objects of my invention is to provide a universal, highly efficient, two-way communication system, instantly operable by merely plugging into any A. C. or D. C. electrical power line circuit and which can be built cheaply and operated with simplicity; and so compact and light in weight as to be readily portable.

10 A second object of my invention is to provide a novel method of loud speaker intercommunication over the electrical power line circuits from point to point without the use of a microphone, utilizing the same loud speaker for both transmission and reception. Obviously this system is to operate both interior and exterior to a meter box, namely, for both inter-room or office use 15 and point to point use on a common power network.

20 A third object of my invention is to provide novel effective means of filtering and eliminating all extraneous and power line noises or interferences, including such inherent noises as D. C. commutator ripples and 60 cycle hums, by coupling the modulated carrier frequency output to the power line circuit through an effective bridge 25 and condenser filter network, thus accomplishing absolutely quiet two-way loud speaker communication and maintaining quality of tone and fidelity of speech, without distortion or attenuation, with a maximum of output volume, and 30 thus permitting housing of both transmission and reception in one small compact unit.

35 Other objects, and the manner in which the same are obtained, will appear from the following description.

40 My system as herein described, is generally applicable to line wire systems, such as telephone, electric light, power, and other lines including metallic rails, and I intend no limitations upon the uses to which my invention may 45 be applied.

45 My invention will be more clearly understood by reference to the accompanying drawing which illustrates a diagrammatic view of one arrangement of apparatus and circuits embodying the 50 improvements of my invention, illustrating the use of a loud speaker as both transmitter and receiver, together with a remote power line control switching, signalling and indicating means.

55 Referring to the drawing, which shows a preferred embodiment of my invention, it will be seen

that the objects of my invention are accomplished by a novel unitary circuit arrangement acting both as a transmitter and a receiver. Used as a transmitter, by impressing a radio frequency carrier wave of predetermined frequency on the electric power line by means of a stable oscillator circuit in any manner well known to the radio art, and then amplifying the voice by means of a voltage amplifier coupled to a modulation means, thus modulating the carrier wave frequency, the output of which is coupled to the power line through a bridge and condenser filter network; and then by means of a selector switch system, utilizing the same tubes for receiving, a highly efficient two-way loud speaker power line 15 communicating system is provided in one small portable unit.

From the following detailed description of the circuit arrangement, it will be obvious to those skilled in the art how the foregoing is accomplished.

20 In transmitting: For transmission purposes, the switch indicated at S in the drawing and comprising the bridging members s₁, s₂, s₃, s₄, s₅, and s₆, is rotated clockwise one step from the 25 position shown in the drawing. An electronic tube V₂ is used for the dual purpose of oscillator and modulator. Grids 1 and 2, together with an oscillator transformer OC, accurately tuned and adjusted, are used as an oscillator stage to furnish a carrier wave, whose frequency may be in the low intermediate frequency spectrum. Grid 4 is used as a modulator grid upon which is impressed the output voltage from the tube V₁, which is used as a voltage amplifier for the microphone currents generated by the voice. The carrier wave is coupled to the modulator through the electron stream of the tube V₂ in such a way that the output of the tube V₂ is a modulated carrier wave. This component is now selected by a very accurately tuned and adjusted resonance system, composed of a selective tuned 30 interstage coupling transformer IC, feeding the modulated carrier wave to the input grid CG' of the tube V₃, which is used as an output stage, amplifying this signal and feeding it to the power line through a double-tuned output transformer OT. The coupling of the output transformer OT to the load may be accomplished by any one of several different network methods. To permit a maximum power transfer to the power line, and to reduce the clicks and noise reproduction, due to intermittent contacts in external circuits, the 35 condensers C₁, C₂ and C₁₉ are used to make the 40 45 50 55

output impedance of the final stage the same as the power line impedance at the operating frequency. Hum modulation, caused by the rectifier tube V_4 , which is connected across the power line L , as well as hum pick-up in the loud speaker voice coil VC , which is being used as a microphone, is eliminated by the use of an R. F. choke RC , connected in series with the rectifier plates P_4-P_5 .

10 Through the selector switch system contact A , the tube V_1 control grid CG , is connected by contact AT and switch bridging member s_1 , to the loud speaker used as a microphone through speaker transformer ST , the return connection 15 being left grounded. The V_2 oscillator grid 1 is connected by contact D and switch bridging member s_3 to the oscillator coil grid condenser C_{12} , by contact DT , and grid leak R_{10} shunts grid resistor R_9 . Through contact E to ET and 20 switch bridging member s_2 , the V_2 circuit is made very sensitive to impulses on the modulator grid 4 , by shorting out a portion of the bias resistor R_8 , to prevent grid rectification during 25 the positive swing of the grid voltage, which when sufficient in voltage on transmitting to give full modulation without grid current, is not enough on receiving to give a satisfactory output. The V_3 control grid CG , is connected by contact B and switch bridging member s_5 , 30 through contact BT , to the grid end of the interstage coupling transformer IC , the return connection being left grounded. Through contact C to CT and switch bridging member s_4 , the V_3 plate P_3 is connected to the output transformer OT , though condenser C_{16} , the return 35 connection being left grounded. Through contact F to FT and switch bridging member s_6 , the condenser C_{19} is shunted by condenser C_2 to change the impedance of the output circuit.

40 When the switch S is positioned for transmission, it will appear that the high frequency generator or oscillator and the amplifier tubes are electrically connected as components of a transmission circuit. This places the loud speaker 45 LS in a position to function as a translating device or an audio sound pickup. The audio frequencies are impressed upon V_1 which serves as an amplifier of the voice frequencies by the action of the speaker as a translating device.

50 The output of V_1 or the amplified voice frequencies are fed into the grid 4 of the tube V_2 , which functions as a high frequency oscillator and which is modulated by the voice frequencies received from amplifier tube V_1 . The audio 55 modulated carrier output of the tube V_2 is coupled to the grid CG' of the tube V_3 through the contacts BT and B and bridging member s_5 of the switch S . The output tube V_3 is fed through the circuit system OT to the lines by 60 means of plug P . In other words, in transmitting position the output of tube V_3 is coupled to the metallic transmission media or power line through the circuit, from the plate P_3 through the condenser C_{16} to the contacts $C-CT$ and bridging member s_4 of the switch S , thence to the condenser C_{17} of the coupling means OT and thence through such means. From the common terminals of condensers C_{18} and C_{19} connection is made to the ungrounded or high side 65 of the power line through contacts $F-FT$ and bridging member s_6 of switch S , condenser C_2 and plug P . Connection is made to grounded line through the remaining terminal of condenser C_{19} by direct path through plug P .

70 When the switch S is in receiving position the

modulated carrier frequency passes from the metallic media or power line through the plug connection P .

The live side of the line through plug P is connected through condenser C_1 and contacts $F-FR$ and bridging member s_6 of switch S to the common terminals of condensers C_{18} and C_{19} . The remaining terminal C_{19} as before connects with the grounded line at plug P . Coupled circuit system OT now serves as an input 10 transformer. The incoming modulated carrier frequencies received from the lines via plug P pass through system OT to the circuit containing condenser C_{17} . One terminal of C_{17} connects through condenser C_4 , contacts $DR-D$ and 15 bridging member s_3 of switch S to the control grid 1 of tube V_2 which now functions as a diode detector, rectification taking place between cathode K_2 and grid 1 . The audio frequency components are then passed through contacts $D-DR$ and bridging member s_3 of switch S , resistance R_{13} , condenser C_5 , contacts $AR-A$ and bridging member s_1 of switch S to control grid CG to tube V_1 which functions as an audio frequency amplifier. The amplified output is 25 passed from plate P_1 through filtering system C_9, C_{10}, R_4, R_5 , and R_6 , thence through condenser C_{22} to contacts $BR-B$ and bridging member s_5 of switch S to control grid CG' of the tube V_3 which serves as a second audio frequency amplifier. The amplified output of V_3 follows the path plate P_3 , condenser C_{16} , contacts $C-CR$ and bridging member s_4 of switch S to transformer ST which supplies loud speaker LS .

The present invention when installed in one residence, office, or building can be made to function independently of similar apparatus installed in other locations in the vicinity, or other apartments or offices in the same building. This results from the fact that the meter M , installed by the power companies at the inlet from the feeder line L , to each residence, office or building, serves substantially to prevent control impulses and/or the carrier wave frequency applied to the lighting system in one residence, office or building from affecting similar apparatus located in another residence, office or building.

The basis of this expedient may be applied 50 generally to arbitrarily section off a line for remote control and/or communication purposes by insertion of small inductances between line sections it is thus desired to isolate.

By shunting the proper capacity condensers $MC-MC'$, across the meter terminals M ,—Figure 1, the blocking effect of the inductance of the meter winding will be obviated, thus permitting transmission and control beyond the meter.

By impressing the proper carrier-wave frequency, such a frequency being selected to overcome the blocking effect of any anticipated or predetermined line load impedances, on to the electric power line circuit L , and by providing sufficient power in the oscillator output, the carrier wave frequency can be conveyed beyond the inductance in the meter M , or line blocking means, onto the power feeder lines L , thus carrying communications anywhere on the power and/or lighting lines.

The drawing shows a jack J , so inserted in the output circuits by connections to the selector switch S , that when it is desired, one may insert a plug, attached to a pair of head phones into the jack J , and disconnect the loud speaker 75

LS, when the selector switch is in receiving position R.

I wish it to be understood that I do not desire it to be limited to the exact details of construction and design as shown, for obvious modifications of the invention within the scope of the appended claims may occur to a man skilled in the art.

Having thus described my invention, what I claim and desire to secure by United States Letters Patent, is:

1. A two-way loud speaker communicating apparatus for use on electric power line circuits and other metallic transmission media, comprising a carrier frequency oscillator, means including a translating device for modulating said carrier frequency, means for amplifying said modulated carrier frequency, means including switching means, for coupling the output of said amplifying means to said metallic transmission media, or for coupling the metallic transmission media to the input of said modulating means and for switching said translating device from said modulating means into the output of said amplifying means, whereby said modulated carrier frequencies received from said metallic transmission media, are detected and reproduced in said translating device.

2. A two way carrier frequency communication system for use on electric power line circuits and other metallic transmission media, comprising in combination a carrier frequency oscillator, means including amplifying means and a translating device for modulating said carrier frequency oscillator, means including a switching means for connecting the output of said oscillator to said metallic transmission media, or for connecting the metallic transmission media to the input of said modulating means and for switching said amplifying means and translating device into the output of said modulating means whereby the modulated carrier frequencies received from said metallic transmission media are demodulated and reproduced in said translating device.

3. A two way loud speaker communicating apparatus for use on electric power circuits and other metallic transmission media, comprising, in combination, a carrier frequency oscillator, means including a translating device for modulating said carrier frequency, means for amplifying said modulated carrier frequency, means, including switching means, for coupling for transmission purposes the output of said amplifying means to said metallic transmission media, and for coupling for reception purposes the metallic transmission media to the input of said modulating means and for switching said translating device from said modulating means into the output of said amplifying means, whereby said modulated carrier frequencies received from

said metallic transmission media are detected and reproduced in said translating device.

4. A unitary transmitting and receiving carrier frequency communication apparatus for use on electric power line circuits and other metallic transmission media comprising in combination common means for both transmission and reception, said means including a carrier frequency oscillator, means including amplifying means and a translating device for modulating said carrier frequency oscillator, means including switching means for connecting for transmission purposes the output of said oscillator to said metallic transmission media, and for connecting for reception purposes the metallic transmission media to the input of said modulating means and for switching said amplifying means and translating device into the output of said modulating means, whereby the modulated carrier frequencies received from said metallic transmission media are demodulated and reproduced in said translating device.

5. In a signaling device adapted for both transmission and reception, the combination comprising a modulator-oscillator, an audio frequency amplifier coupled to the input thereof, a microphone coupled to the input of the audio frequency amplifier, a radio frequency amplifier coupled to the output of the modulator-oscillator, and means including switching means connected to the coupling means for conditioning them so that the oscillator-modulator becomes a detector connected to the input of the audio frequency amplifier, the radio frequency amplifier is coupled to the output of the audio frequency amplifier and the output of the radio frequency amplifier is connected to the microphone, whereby the microphone becomes a loud speaker.

6. In a signaling device adapted for both transmission and reception, the combination comprising a modulator-oscillator, an audio frequency amplifier coupled to the input thereof, a microphone coupled to the input of the audio frequency amplifier, a radio frequency amplifier coupled to the output of the modulator-oscillator, means including switching means connected to the coupling means for conditioning them so that the oscillator-modulator becomes a detector connected to the input of the audio frequency amplifier, the radio frequency amplifier is coupled to the output of the audio frequency amplifier and the output of the radio frequency amplifier is connected to the microphone whereby the microphone becomes a loud speaker, and a low radio frequency impedance network for coupling the output of the radio frequency amplifier to a transmission line and for coupling the transmission line to the input of the modulator-oscillator for transmission and reception respectively.

SOL J. LEVY.
